UNITED STATES PATENT OFFICE.

WILLIAM E. WOODARD, OF SCHENECTADY, NEW YORK, AND SAMUEL S. RIEGEL, OF SCRANTON, PENNSYLVANIA.

LATERAL-MOTION APPLIANCE FOR LOCOMOTIVE DRIVING-BOXES.

1,181,194.

Specification of Letters Patent.

Patented May 2, 1916.

Application filed January 3, 1916. Serial No. 70,002.

To all whom it may concern:

Be it known that we, WILLIAM E. WOODARD, of Schenectady, in the county of Schenectady and State of New York, and SAMUEL S. RIEGEL, of Scranton, in the county of Lackawanna and State of Pennsylvania, have jointly invented a certain new and useful Improvement in Lateral-Motion Appliances for Locomotive Driving-Boxes, of 10 which improvement the following is a specification.

Our invention relates to means for affording and controlling lateral motion in the driving boxes of locomotive engines, and its 15 object is to provide an appliance of such type which shall be of simple construction and ready applicability in locomotives of the various present standard types, with the operative result of enabling a locomotive 20 having a comparatively long rigid wheel base to pass through curves of comparatively short radius, without liability to derailment, and without inducing undue or excessive wear of wheel flanges and rails. 25 The improvement claimed is hereinafter fully set forth.

It is now well recognized that one of the principal factors that have limited the increase in size of locomotives, has been the 30 length of rigid wheel base which is safely operable over existing railroad tracks. When the driving or rigid wheel base of a locomotive exceeds a certain length, it will not pass track curves of ordinary radii without cramping the wheels in the curvature of the track, thereby inducing undue flange pressure and wear upon the wheel tires and rails, or requiring excessive increase of gage. If the rigid wheel base is carried to the extreme, the result may be the overturning of the rails or the derailment of the locomotive. Several expedients have been heretofore essayed, in order to obviate or lessen the objections that have been developed as 40 the driving wheel bases have been lengthened. One of these consists in drawing in the tires of the first and last pairs of driving wheels to a lesser dimension than the tire setting of the remaining driving wheels. 45 Another plan that has been practised is to arbitrarily allow greater lateral play between the wheel hubs and driving boxes of 50

the front and rear driving axles, or of the front driving axles only, than between those of the other driving axles. The driving wheels which are so given additional lateral movement are consequently permitted a corresponding degree of deflection in passing curves, whereby the tendency to bending or cramping is reduced. Again, in foreign 55 practice, the leading pair of driving wheels has been combined with a pair of leading wheels, in a truck structure, in such manner that the leading driving wheels partake in the lateral motion of the truck structure. 60

It will be obvious that in order that a pair of driving wheels having lateral motion shall properly perform its function, in assisting to guide the locomotive, that this pair of wheels shall be subjected to a definite lateral resistance against deflection, as otherwise, they would simply roll along the track without offering any resistance to the lateral motion of the locomotive until the limit of their side motion is taken up. The 70 ideal disposition of driving wheels having lateral motion is therefore one in which a definite resistance is exerted against any tendency to side motion, this resistance being preferably, proportionate to the weight 80 on the lateral motion driving wheels, which, as so disposed, assist in guiding the locomotive under all conditions. It will, further, be obvious that it is desirable to provide guiding means which shall be independent of a truck, so that lateral motion driving wheels may be applied either in a locomotive having no trucks, as one of the 85 0-10-0 type, in one having a two wheel or a four wheel truck, as one of the 2-10-2 or 4-10-2 type, or that they may be located in any desired position in the driving wheel system, as being the middle or the rear pair of driving wheels. 90

Our invention is designed to overcome the 95 objections and answer the requirements above set forth, and to materially reduce the lateral thrusts or blows from locomotive driving wheels which are recognized as being one of the most serious of the 100 forces which injure and deform railroad tracks, and which are intimately related to the amount of lateral motion allowed between driving wheel hubs and axle boxes.

This result is attained by the means which we provide for distributing the pressure over two or more pairs of driving wheels and cushioning the effect of lateral motion 5 by the application of a yielding lateral resistance.

In the accompanying drawings: Figure 1 is a diagrammatic side view, in elevation, of a locomotive, illustrating an application 10 of our invention; Fig. 2, a view, the left hand half of which is an outside view, in elevation, of a locomotive frame pedestal, illustrating an application of our invention, and the right hand half, a vertical section on 15 the line *a a a a* of Fig. 3; Fig. 3, a view, partly in vertical transverse section at the middle of the pedestal, and partly in elevation, showing a driving box and its accessories; Fig. 4, a view, showing a structural modification, the left hand half being an elevation taken similarly to Fig. 2, and the right hand half, a vertical section on the line *b b* of Fig. 5; Fig. 5, a view taken similarly to Fig. 3; Fig. 6, a view, showing another 20 structural modification, the left hand half being an elevation, taken similarly to Figs. 2 and 4, and the right hand half, a vertical section on the line *c c c c* of Fig. 7; Fig. 7, a view, taken similarly to Figs. 3 and 5; Figs. 8 25 and 9, views, on a reduced scale, taken similarly to the upper portion of Fig. 7, showing modified forms of lateral motion bearings; Fig. 10, a view, showing another structural modification, the left hand half being an elevation, taken similarly to Figs. 2, 4 and 6, and the right hand half, a vertical section on the line *d d* of Fig. 11; Fig. 11, a view, taken similarly to Figs. 3, 5 and 7; Fig. 12, a partial plan view, on a reduced 30 scale; Fig. 13, a view, showing another structural modification, the left hand half being partly an elevation, taken similarly to Figs. 2, 4, 6 and 10, and partly a vertical section on the line *e e* of Fig. 14, and the 35 right hand half, a vertical section on the line *f f f f* of Fig. 14; and Fig. 14, a view, taken similarly to Figs. 3, 5, 7 and 11.

Our invention is herein exemplified as applied in connection with a locomotive 50 engine, the frame of which is of the standard "bar" type, and comprises two side members, which are, as in present standard practice, spaced at the maximum distance apart available under the necessary limitation 55 imposed by the width between driving wheel hubs. Each of the side frame members comprises, so far as the portion thereof in which the driving axles are fitted is concerned, the usual top rail, 1, bottom rail, 2, and connecting vertical pedestals, each of which consists of a pair of pedestal jaws, 3, in which one of the end portions of a driving box, 4, is fitted between a wedge, 4^a, and a shoe, 4^b, in the ordinary manner. The 60 open spaces between the sections of the

lower frame rail at the bottoms of the pedestals are spanned by pedestal ties, 5, suitably connected to the bottom frame rail.

Referring first to Figs. 1 to 3 inclusive, in the practice of our invention, the driving boxes, 4, of each of the driving axles in connection with which the invention is applied, are, in this exemplification, shown as being of substantially greater length than those in ordinary practice, and as being 70 provided with flanges, 4^c, on their ends, the outer flanges abutting against the hubs of the driving wheels, 6. The transverse central planes of the driving boxes are located slightly inside of the frame members, and 75 clearance space equal to the extent of lateral motion desired, is interposed between the outer flanges and the shoes and wedges, as indicated at *x* in Fig. 3. The proper spacing of the driving boxes on the axle is effected 80 by a bridge, or spacing member, 7, of substantially inverted U section, which extends parallel with the driving axle, 8, and rests upon the boxes at about the middle of their length, and also engages their inner end 85 flanges, thus connecting the driving boxes longitudinally and maintaining the determined clearance between the shoes and wedges and the outer flanges of the driving boxes.

The portion of the weight of the locomotive which is carried on the driving axle, 8, is transmitted to the driving boxes, 4, through springs, 9, which bear centrally on seats, 10^a, at the ends of a spring supporting beam, 10, extending transversely of the locomotive, above the bridge, 7, and adapted to move vertically, but not laterally, relatively to the side frame members. It will, of course, be understood that the springs are 100 connected, by hangers at their ends, to the side frame members, either directly or through the intermediation of equalizers, as in ordinary practice. The supporting beam is guided in its vertical movements, by vertical guide faces, 10^b, projecting downwardly 105 below the spring seats, and fitting, with only working clearance, against rubbing surfaces, as plates, 1^a, secured to the top frame rails, 1. The supporting beam, 10, is, in 110 turn, supported on the bridge, 7, and connected driving boxes, 4, through rockers, 11, which are of the type set forth in Letters Patent of the United States No. 1,060,222, granted and issued to William E. Woodard, 115 under date of April 29, 1913, and are not, in and of themselves, included in our present invention. The rockers, 11, are interposed between the supporting beam, 10, and the bridge, 7, adjacent to the ends of the 120 latter, and each of them is provided at bottom with journals, 11^a, fitting in open topped bearings in the bridge, 7, and with oppositely curved or inclined bearing faces, 11^b, on their tops, upon which the supporting 125 beam rests.

- beam bears, through correspondingly inclined bearing faces, 10^a , on its bottom. It will be apparent that in other particulars the constructions being as above described, the two driving boxes may, if desired, be formed in an integral casting with flanges on the inner sides of the pedestal shoes and wedges serving as stops when the integral box casting moves to either limit of its lateral traverse, the outer flanges of the driving boxes being dispensed with, and the outer ends of the boxes being enlarged so as to be equal in width to the greatest diameter of the driving wheel hubs. A driving box structure of such type is described and shown in Letters Patent of the United States No. 1,141,294, granted and issued to William E. Woodard, under date of June 1, 1915.
- In the operation of a locomotive, in which a construction embodying the essential features of that above described, or their equivalents, is applied, when the driving boxes and connecting bridge or spacing member, 7, are laterally deflected, in either direction, from their normal position relatively to the side frame members, by a lateral movement of the driving wheels, as, for example, would be resultant upon the passage of the locomotive from a straight to a curved portion of the track, their lateral movement swings each of the supporting rockers, 11, upon one or the other pair of its journals, 11 a , in direction opposite to that of the movement of the driving boxes. This movement of the rockers, which acts to raise the supporting beam, 10, is resisted by the weight borne thereon, this resistance acting through the inclined bearing faces, 10^a , on its bottom, on the curved bearing faces, 11 b , at the tops of the rockers, and depending, in degree, on the relation of their height to the horizontal distance of their pairs of journals. The beam, 10, being prevented from moving laterally, the springs, 9, participate in its vertical movement, as the resistance stated is overcome, without disturbance of their lateral relation to the side frame members or equalizer connections. When the locomotive passes from the curve to a tangent of the track, the superimposed weight on the rockers returns them, and the driving boxes, to their normal central positions indicated in Fig. 3.
- The structural modification shown in Figs. 4 and 5, complies in all essential particulars with the construction first above described, and differs therefrom in the substitution of swing links for the supporting rockers, 11, and in the form of the bridge, 7. The latter, instead of being an integral casting as in the former case, is, in this instance divided into two vertical plate members, which are connected, at their tops, by a horizontal plate member, 7 a , and are provided, at their ends, with downwardly inclined arms, 7 b , which fit in pockets, 4 b , formed in the shoe and wedge faces of the driving boxes, 4. The weight borne by the supporting beam, 10, acts on the bridge, 7, and connected driving boxes, through three point swing links, 14, of the same general design as those applied in locomotive trucks, each of said links being hung upon two parallel pins, 14 a , fixed in the bridge, 7, and being coupled to the supporting beam, 10, by pins, 14 b , the axes of which are parallel with, and disposed in vertical planes midway between, those of the pins 14 a , of the supporting beam. The operation of this construction is similar to that of the design shown in Figs. 2 and 3.
- Figs. 6 to 9 inclusive, illustrate other modifications of structural design. As shown in Figs. 6 and 7, rockers, 15, substantially similar to those of Figs. 2 and 3, are interposed between the driving boxes and the supporting beam. In Fig. 8, the supporting beam bears directly on the driving boxes, through downward projections near its ends having double inclined faces, 10 c , at their bottoms, which rest on correspondingly inclined bearing faces, 4 b , on the driving boxes, and in Fig. 9, rollers, 16, are shown as interposed between bearing faces, 10 c , on the bottom of the supporting beam, and concave bearing faces, 4 c , on the tops of the driving boxes.
- The structural modification shown in Figs. 10 to 12 inclusive, accords generally with that of Figs. 2 and 3, the driving boxes, 4, being connected by a bridge or spacing member, 7, and the springs, 9, bearing on a supporting beam, 10, which rests on rockers, 11, journaled in the bridge, these being of substantially similar form as, and operating similarly to, those shown in Figs. 2 and 3. The clearance between the tops of the driving boxes and the top rails, 1, of the main frame members, is, in this case, increased, and driving boxes of normal length are applied, the bridge, 7, being engaged therewith in their middle vertical transverse planes, and in the same plane of the frame rails. The disposition of the driving boxes, relatively to the top frame rails, enables the supporting beam to be lowered sufficiently for the transverse distance between the springs, 9, to be reduced, so that their bearings on the beam will be approximately over the rockers, as shown in Fig. 11. Inasmuch as lateral motion driving boxes are more particularly designed for application in connection with a two wheel or a four wheel truck which is connected with the equalizing system of the driving wheels through a cross equalizer located forward of the first pair of driving wheels, and a long equalizer to the center pin of the truck, the distance between the forward ends of the front driv-

ing springs may be decreased, as shown in Figs. 11 and 12. In this modification, the weight of the supporting beam is reduced and the driving springs are lowered, relatively to the frame members.

Figs. 13 and 14 illustrate another structural modification, in which the medium which exerts resistance to lateral motion of the driving boxes, 4, consists of a system of springs independent of the ordinary driving springs, 9, which latter springs are, in this instance, supported on the driving boxes by spring saddles, 9^a, which straddle the top frame rails, 1, in the usual manner. The driving boxes are provided with end flanges, 4^a, adapted to abut against the pedestal shoes and wedges. The top frame rails, 1, are connected by a cross tie, 16, which extends from one frame rail to the other in the vertical plane of the driving axle, 8, and is secured, at its ends, to the frame rails, by bolts, 16^a. Two bell crank or elbow levers, 17, are journaled on pins, 17^a, fitted in the cross tie, 16, adjacent to the frame rails, the lower arms of said levers being forked to extend on opposite sides of the driving axle, and having bearings, 17^b, on their ends, adapted to abut against the inner ends of the driving boxes. A plurality of helical springs, 18, is disposed vertically in the cross tie, 16, said springs extending between upper spring seats, 18^a, and lower spring seats, 18^b, the latter of which normally bear on supports, 16^b, which, in turn, bear on a plate, 16^c, secured detachably to the bottom of the cross tie, by bolts, 16^d. The tension of the springs may be adjusted as desired, by set screws, 18^e, bearing on the upper spring seats. The ends of the upper arms of the levers, 17, fit under and against the lower spring seats, 18^b, and, when the driving boxes are in the normal central positions which they occupy when the locomotive is on a tangent of the track, the levers are not subjected to pressure from the springs, 18. When, however, the locomotive passes to a curve and the driving boxes are thereby laterally deflected in either direction, one of them presses against the bearings, 17^b, of the lower arm of the adjacent lever, 17. The upper arm of said lever will thereby be pressed upwardly against the lower spring seat, 18^b, and the lateral movement of the driving boxes will be resisted by the compression of the springs, 18.

It will be observed that in each of the several constructions herein exemplified, there is embodied a bridge or spacing member which maintains the two driving boxes at a determined distance apart. This structural feature is materially important and desirable, from a mechanical and operating standpoint, for the reason that if the driving boxes were not combined with a connect-

ing member of such character, the wheel hub on one side would draw away from the adjacent driving box when the opposite wheel hub was pressing inwardly against its adjacent driving box. This condition would result in abnormal lateral play on one side between the driving box and the wheel hub, with the consequent possibility of a heavy blow between them when the wheels and axle return to normal position. Moreover, the provision of the spacing member insures that when there is lateral pressure of either of the wheel hubs upon the adjacent driving box, the centering force is that resulting from the weight borne by the two driving boxes, irrespective of the position of the other driving box relatively to its wheel hub. An additional consideration for the provision of the bridge or spacing member will be found in the recent ruling of the Interstate Commerce Commission, fixing a maximum allowable limit for lateral clearance between wheel hubs and boxes. In order to be acceptable under this ruling, it is necessary that means for maintaining the normal relation of the driving boxes and wheel hubs shall be provided in any proposed construction of lateral motion driving boxes.

It will be obvious that the essential elements of the several embodiments of our invention hereinbefore described, may be varied in structural detail, and in their combinations, without departure from the spirit and operative principle of our invention. For example, while we have shown and described the two driving boxes and the spacing member thereof as being separate but connected parts, and consider such to be the preferable construction for facility of manufacture and installation, said driving boxes and spacing member may, if preferred, be formed in an integral casting, which, operatively, would constitute a mechanical equivalent of the separate and connected parts herein set forth. We do not, therefore, limit ourselves, in the practical application of our invention, to the specific forms of construction in which it is herein exemplified.

Our invention attains a material and substantial advantage in practice, by enabling the operation of large locomotives, having five or more coupled axles, to be facilitated on lines of railroads, the degrees of curvature of which do not exceed those which are generally considered to be admissible, and to be rendered practicable where curves of shorter radius are required to be traversed. A locomotive fitted with self centering driving boxes in accordance with our invention can be equipped with flanged tires throughout, set at a uniform distance apart. In other words, a common standard of tire setting, uniform for all wheels, would be

brought about, and, further, it would be possible to adopt a standard track gage for the rails on all curves. The advantage, in the attainment and adoption of standard 5 and uniform practice, will be obvious to those familiar with the conditions of railroad service.

We claim as our invention and desire to secure by Letters Patent:

10. 1. In a locomotive engine, the combination of two side frame members; two independent driving boxes, each fitted with the capacity of relative vertical and lateral movements in one of said frame members; a driving axle journaled in said driving boxes; driving wheels fixed on said driving axle; and means, detachably connected to the driving boxes, for maintaining their determined lateral spacing on the driving axle.
15. 2. In a locomotive engine, the combination of two side frame members; two independent driving boxes, each fitted with the capacity of relative vertical and lateral movements in one of said frame members; a driving axle journaled in said driving boxes; driving wheels fixed on said driving axle; means, detachably connected to the driving boxes, for maintaining their determined lateral spacing on the driving axle;
20. 3. In a locomotive engine, the combination of two side frame members; two independent driving boxes, each fitted with the capacity of relative vertical and lateral movements in one of said frame members; a driving axle journaled in said driving boxes; driving wheels fixed on said driving axle; means, detachably connected to the driving boxes, for maintaining their determined lateral spacing on the driving axle;
25. 4. In a locomotive engine, the combination of two side frame members; two independent driving boxes, each fitted with the capacity of relative vertical and lateral movements in one of said frame members, and having its transverse central plane on the inner side of the corresponding plane thereof; a driving axle journaled in said driving boxes; driving wheels fixed on said driving axle; and means, detachably connected to the driving boxes, for maintaining their determined lateral spacing on the driving axle.
30. 5. In a locomotive engine, the combination of two side frame members; two independent driving boxes, each fitted with the capacity of relative vertical and lateral movements in one of said frame members, and having its transverse central plane on the inner side of the corresponding plane thereof; a driving axle journaled in said driving boxes; driving wheels fixed on said driving axle; means, detachably connected to the driving boxes, for maintaining their determined lateral spacing on the driving axle;
35. 6. In a locomotive engine, the combination of two side frame members; two independent driving boxes, each fitted with the capacity of relative vertical and lateral movements in one of said frame members; a driving axle journaled in said driving boxes; driving wheels fixed on said driving axle; a detachable bridge or spacing member connecting the driving boxes; driving springs subjected to weight borne by the side frame members; a vertically movable supporting member carrying said driving springs; and means for transmitting pressure from said supporting member to the spacing member.
40. 7. In a locomotive engine, the combination of two side frame members; two independent driving boxes, each fitted with the capacity of relative vertical and lateral movements in one of said frame members; a driving axle journaled in said driving boxes; driving wheels fixed on said driving axle; a detachable bridge or spacing member connecting the driving boxes; driving springs subjected to weight borne by the side frame members; a vertically movable supporting member carrying said driving springs; and means for transmitting pressure from said supporting member to the spacing member.
45. 8. In a locomotive engine, the combination of two side frame members; two independent driving boxes, each fitted with the capacity of relative vertical and lateral movements in one of said frame members; a driving axle journaled in said driving boxes; driving wheels fixed on said driving axle; a detachable bridge or spacing member connecting the driving boxes; driving springs subjected to weight borne by the side frame members; a vertically movable supporting member carrying said driving springs and guided by and between the side frame members; and means for transmitting pressure from said supporting member to the spacing member.
50. 9. In a locomotive engine, the combination of two side frame members; two independent driving boxes, each fitted with the capacity of relative vertical and lateral movements in one of said frame members; a driving axle journaled in said driving boxes; driving wheels fixed on said driving axle; a detachable bridge or spacing member connecting the driving boxes; driving springs subjected to weight borne by the side frame members; a vertically movable supporting member carrying said driving springs; and relatively movable bearing devices through which pressure is transmitted from the supporting member to the spacing member.
55. 10. In a locomotive engine, the combination of two side frame members; two independent driving boxes, each fitted with the capacity of relative vertical and lateral movements in one of said frame members; a driving axle journaled in said driving boxes; driving wheels fixed on said driving axle; a detachable bridge or spacing member connecting the driving boxes; driving springs subjected to weight borne by the side frame members; a vertically movable supporting member carrying said driving springs; and relatively movable bearing devices through which pressure is transmitted from the supporting member to the spacing member.

tion of two side frame members; two driving boxes, each fitted with the capacity of relative vertical and lateral movements in one of said frame members; a driving axle 5 journaled in said driving boxes; driving wheels fixed on said driving axle; a bridge or spacing member connecting the driving boxes; driving springs subjected to weight borne by the side frame members; a verti-

cally moving supporting member carrying 10 said driving springs; and vibratable rockers interposed between and bearing on the supporting member and the spacing member.
